UNITED STATES PATENT OFFICE.

JOSEPH A. PAULLIN, OF MEXICO, MISSOURI.

DETONATING RAILROAD-TRACK SIGNAL.

SPECIFICATION forming part of Letters Patent No. 269,955, dated January 2, 1883.

Application filed July 11, 1882. (No model.)

To all whom it may concern:

Be it known that I, JOSEPH A. PAULLIN, a citizen of the United States of America, residing at Mexico, in the county of Audrain and State of Missouri, have invented certain new and useful Improvements in Detonating Railroad-Track Signals; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to detonating railroad-signals; and it consists in certain features hereinafter described, and specifically set forth in the claims.

Figure 1 is an enlarged view of the devices 20 for setting the signal upon the rail. Fig. 2 is a perspective of my entire device.

Like letters refer to like parts in both figures.

A represents a portion of the rail, and B represents the base-piece of my device, which 25 is adapted by the hook b to be secured beneath the rail and upon one of its flanges, as shown.

To the base-pieces at b' is secured pivotally an arm, C, slotted at c to pass over a staple, c', secured to the base-piece, whereby by means 30 of the padlock D the arm may be secured in a closed position, so that the entire device is secured to the rail permanently in such manner that it cannot be removed by unauthorized persons, the hook b and arm C serving to firmly 35 clamp the flanges of the rail, as shown.

The step or projection c² is provided on the arms C in order that the cap E shall not bear upon the flange of the rail when the arm is closed with sufficient force to explode or injure 40 the same.

The cap E is placed upon or suitably secured to a plunger, F, which works within the outer hollow end, G, of the arm, and when closed the plunger projects sufficiently above the 45 tread of the rail to be depressed by wheels running upon the rail.

The base-piece B is extended and bent at right angles to form a standard, B', to which is secured by straps d a sign or flag, H, of suitable design or coloring, which may be the same 50 on both sides; or it may, if desired, differ in design upon each side.

To the top of the standard B' is secured any ordinary signal-lantern, I, which is adapted to be rotated so as to present the glasses i of different colors in desired direction.

It will be seen that the whole device is portable, so that in case of danger an approaching train may be warned by signals which are perceptible both audibly and visibly by day or 60 night, the explosion of the cap producing a report as the wheels of a train pass over the plunger, insuring attention to the signals which are visible in case they are not seen before the train explodes the cap.

Having described my invention and its operation, what I claim as new, and desire to secure by Letters Patent, is—

1. The combination of the base-piece B, provided with the hook b and staple c', with the 70 pivotally-attached arm, slotted for the reception of the staple, and provided with a plunger, F, to explode a cap, substantially as shown and described.

2. The base-piece B, provided with the hook b, the swinging arm C, adapted to carry a plunger and to be secured to the rail, and extended to form a standard, b', adapted to receive and support a signal-lantern, I, and flag H, substantially as shown and described. 80

3. The combination, with the rail A, of the hooked base-piece, the pivotally-attached arm C, slotted at c and provided with the step c², and with the hollow end G and the plunger F, substantially as shown and described. 85

In testimony whereof I affix my signature in presence of two witnesses.

JOSEPH A. PAULLIN.
